Specification of Letters Patent.

Patented Jan. 2, 1917.

Application filed March 22, 1916. Serial No. 86,033.

To all whom it may concern:

Be it known that we, HENRY B. OATLEY and NEAL T. MCKEE, both citizens of the United States, and residing, respectively, at 5 Flushing, county of Queens, State of New York, and at Yonkers, county of Westchester, State of New York, have invented certain new and useful Improvements in Superheaters, of which the following is a specification.

Our invention relates to superheaters of the type usually known as smoke tube superheaters and used extensively especially in connection with locomotives.

15 In the usual arrangement certain of the fire tubes of the boiler are made of larger size than the others, and the superheater units are located in these larger tubes. The units themselves consist of four lengths of 20 tubing, connected to each other by three return bends, the two free ends being connected to a suitable header or headers usually located in the smokebox. The steam, coming from one compartment of the header, travels first 25 through one of the tube lengths in a direction from the smokebox toward the fire box, reverses its direction just before reaching the firebox, flows forward, is again reversed in a second return bend, travels again toward 30 the fire box, being once more reversed and traveling forward and into a second compartment of the header, whence it is carried to the cylinders. This is well known to those skilled in this art. In the majority 35 of cases the second return bend is located well forward, usually being actually in the smokebox. Under some circumstances and for certain reasons it may become desirable to make the second and third lengths shorter 40 and locate the second return bend some distance back from the front flue sheet. The exact location is not important for purposes of the present invention.

With the arrangement as thus far described certain disadvantages arise which it is the object of the present invention to overcome.

The invention will be best understood by reference to the accompanying drawing, 50 wherein—

Figure 1 is a side elevation of a unit embodying our invention with so much of the boiler shown, partly in section and partly in elevation, as is required to show the relation 55 of the two; Fig. 2 is an enlarged top view of

the unit located in its flue, the latter in section; Fig. 3 is a view, similar to Fig. 2, of a modification; while Figs. 4 and 5 are respectively still more enlarged sectional views of portions of the units of Figs. 3 and 2. In all 60 of the views certain portions are broken away.

Referring first to Fig. 1, 1 and 2 are the fire box and smoke box flue sheets respectively of a boiler; 3 being the shell; and 4, 4 65 being enlarged flues, within which lie the superheater units; 5 is such a unit. While only one unit is illustrated, it is of course understood that there may be any desired number of such units each located in its flue. 70 The ends, 6, 6 of the units are attached in any preferred manner to the header 7. The header receives steam at point 8 from the dry pipe; and after the steam has traversed the superheater units and has returned to the 75 header, it leaves at 9 for the engine cylinders. If the return bend 10 is located back some distance from the front flue sheet as above suggested, the gas section, i. e., the free section for the passage of hot gases, 80 experiences a sudden change at this point. Whereas there are four tubes of the unit in the flue up to this point, there are only two from this point forward. As a result the flow of the hot gases experiences a corresponding sudden diminution of velocity. 85 This check in velocity suddenly lessens the power of the hot gases to carry with them any soot, ashes, and other impurities, and these are therefore dropped and accumulate 90 at this one point. The present invention overcomes this serious defect in a simple and effective manner.

Two lengths of tubing 11, 11 are secured to the return bend 10, being welded or otherwise united to it, and forming continuations of the two tube lengths which are connected to return bend 10, without, however, the wall of the return bend being pierced in any way. There is thus no communication 95 between the tubes 11 and the inside of the superheater unit. This will be clear especially from Fig. 5. The effect as far as the hot gases in the flue are concerned is that their velocity receives no sudden check, 100 but diminishes normally with their gradual cooling, just as is the case when return bend 10 is located at or forward of the front flue sheet.

In the modification shown in Figs. 3 and 110

4 the return bend 10 is left in its usual position just forward of the front flue sheet; but the two tube lengths which it connects are further connected by a cross-connection 5 at a point 12, the exact location of which is again a matter of choice, determined mainly by the boiler proportions. By properly proportioning the size of the cross-connection 12 the relative amounts of steam 10 passing through it and through return bend 10 respectively can be made practically whatever we please. By making it large enough, the steam in the part of the unit forward of this point is practically stagnated, all of the steam going to the cylinders 15 passing through 12. That part of the unit forward of 12 therefore adds nothing to the superheat of the steam, but does fulfil the requirement of keeping constant the free 20 cross-section for the hot gases. In practice it will prove desirable to make the relative size of cross-connection 12 such that enough steam passes by way of return bend 10 to protect the latter from injury by the hot 25 gases.

Certain modifications are evidently possible. Thus the tubes 11 in the form first described may be closed at their front ends, or connected to each other at the front ends, 30 or replaced by solid bars of the same diameter. Moreover the use to which an element so constructed may be put is not confined to superheating steam, but may be for altering the temperature of any fluid. Such 35 variations evidently come within the spirit of the following claims.

What we claim and desire to secure by Letters Patent is:

1. The combination of a flue, a super- 40 heater unit of the class described within said flue, said unit comprising means to change the direction of flow of steam through it at a point remote from the ends of the flue, and two tubes attached to said

means, their interior however not commu- 45 nicating with the interior of the unit.

2. The combination of a flue, a header, a superheater unit located within said flue and comprising four tube lengths joined *seriatim* 50 by three return bends, the middle return bend being remote from the front end of the flue, the first and the last tube lengths being connected directly to the header, and two pipe lengths extending forward from said middle return bend in such manner 55 that their axes are in line respectively with the axes of the two tube lengths opening into said middle return bend.

3. In a boiler, the combination of a flue, a header, a superheater unit located within 60 said flue, and comprising four tube lengths, means connecting the first to the second, the second to the third, and the third to the fourth length, the first and the fourth lengths being connected directly to the 65 header, the means connecting the second to the third length being located at a point remote from the front end of the flue, and portions independent of the first and fourth 70 lengths extending forward from said last mentioned means and each having the same cross-sectional outline as the tube lengths.

4. In a boiler, the combination of a flue, a header, a superheater unit of the class de- 75 scribed located within said flue and comprising four lengths, two of said lengths communicating at one end directly with the header and at the other end with the remaining two lengths, said remaining two lengths communicating with each other at 80 a point remote from the front end of the flue; and two pipe lengths united to the unit in such manner that their axes coincide with those of the tube length last mentioned, their interior however not communi- 85 cating with the interior of the unit.

HENRY B. OATLEY.
NEAL T. MCKEE.
